UNITED STATES PATENT OFFICE.

GEORGE W. PROUTY, OF MILTON, MASSACHUSETTS.

TICKET-PUNCH.

1,312,492.

Specification of Letters Patent.

Patented Aug. 5, 1919.

Application filed September 14, 1918. Serial No. 254,376.

To all whom it may concern:

Be it known that GEORGE W. PROUTY, a citizen of the United States of America, and a resident of Milton, in the county of Norfolk and State of Massachusetts, has invented certain new and useful Improvements in Ticket-Punches, of which the following is a specification.

This invention relates to ticket punches and has for its object the production of an effective tool of this character which will be simple in construction and cheap to make.

The invention consists in a punch, the body portion of which is made integral with a stripper interposed between the ends thereof, one of said ends being provided with a projecting cutting member adapted to coact with an opening in the other end of said body portion.

The invention further consists in certain novel features of construction and arrangement of parts which will be readily understood by reference to the description of the drawings and to the claims to be herein-after given.

For the purpose of illustrating the invention, one preferred form thereof is illustrated in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Fig. 1 represents an elevation of a ticket punch embodying the principles of the present invention.

Fig. 2 represents a transverse section of the same on line 2, 2, on Fig. 1.

Fig. 3 represents an enlarged longitudinal section of the working end of the punch, and

Fig. 4 represents a transverse section of the same on line 4, 4, on Fig. 3.

Similar characters designate like parts throughout the several figures of the drawings.

In the drawings 10 is the body portion of the punch made U-shaped of spring metal with the disconnected end portions 11 and 12 thereof parallel.

Between the parallel end portions 11 and 12 and the opposite connecting end 13 of the body portion 10 the oppositely disposed portions 14 are curved outwardly as indicated in Fig. 1 and are separated a distance sufficient to afford a good grip when in the hand of the operator.

The outer faces of the curved portions 14 are rounded over as indicated at 15 in Fig. 2, thus affording a smooth surface which will not injure the hand when the device is in use.

The connecting portion 13 is preferably hardened so that sufficient spring will be afforded the body portion without danger of breaking the same in the constant use to which the punch will be subjected.

The end portion 12 is provided with a hole 16 in which is positioned the shank 17 of the projecting cutting member 18 which is preferably cylindrical (but which may be of any shape) in cross section.

The outer end of the cutting member 18 is provided with a depression 19 leaving 80 a cutting edge at the periphery of said cutting member.

The end portion 11 is provided with an opening 20 alined with the cutting member 18 and having the same shape and size as 85 the cross section of said cutting member 18.

This end portion 11 is preferably hardened so that the wall of the hole 20 will coact with the knife edge of the cutting member 18 and effect the punching of any 90 card board material inserted between the cutting member 18 and the inner face of the end portion 11 whenever the operator forces the end portions 11 and 12 together by pressure upon the curved portions 14. 95

The end portion 11 being hardened the end of the cutting member 18 is kept sharp at all times every operation of the device tending to sharpen the cutting member whenever its end enters the hole 20. 100

The outer end of the hole 20 is enlarged as at 21 to facilitate the discharge of the portions punched from the card board ticket.

Between the end portions 11 and 12 is a 105 stripper 22 preferably formed integral with the body portion 10 as shown in the drawings, this stripper 22 being provided with an opening 23 therein of greater diameter than the diameter of the cutting member 18. 110

The end of the portion 11 is curved at 24 and the end of the stripper 22 is curved

downwardly as at 25 thus producing a wide mouth which facilitates the insertion of the card board ticket into the slit between the stripper and the inner face of the end portion 11.

The outer end of the cutting member 18 is normally within the hole 23 so that it will not obstruct the insertion of the card board ticket into the slit 26.

When a ticket has been inserted in the slit 26 the operator applies gripping pressure to the portions 14 and forces the cutting member 18 through the card board into the hole 20 the knife edge of the cutting member 18 and the hardened wall of the hole 20 producing a shearing action during the cutting operation.

The entire body portion and stripper of the device may be produced from a single bar by drop forging and when the hole 23 has been drilled therein the bar may be bent into the shape shown in the drawings and the holes 16 and 20 drilled in alignment.

The cutting member 18 may then be driven into position through the hole 20 and the device is ready for use. This makes a very cheap construction of punch which is very effective in use and which will not readily become inoperative.

It is believed that the operation and many advantages of the invention will be readily understood without further description.

Having thus described my invention, I claim:

1. A ticket punch consisting of a U-shaped curved body portion having formed integral therewith on its ends, three parallel plates, the central plate of which is thinner than the outer plates and said plates having alined openings therethrough, and a cutting member rigidly secured in one outer plate with its cutting end normally positioned within the opening in the central plate and adapted to enter the opening in the other outer plate when said outer plates are forced toward each other.

2. A ticket punch consisting of a U-shaped

curved body portion having formed integral therewith on one end a rigid bed plate and a stripper plate and on the other end a parallel cutter-supporting plate, all of said plates having alined openings therethrough, and a cutting member rigidly secured in the opening in the cutter-supporting plate with its cutting end normally positioned in the opening in the stripper plate and adapted to coact with the opening in the bed plate.

3. A ticket punch having a U-shaped body portion with parallel ends, one of which has a thickness considerably greater than the thickness of the other and is provided with a longitudinal slit with parallel walls formed therein extending from side to side thereof and alined openings in the upper and lower portions of said thicker end perpendicular to said slit, the opening in the outer portion being of less diameter than the opening in the other portion; and a cutting member rigidly secured in the thinner end in alinement with said openings and with its outer end normally positioned in the larger opening.

4. A ticket punch having a U-shaped body portion with parallel ends, one of which is longer and has a thickness considerably greater than the thickness of the other and is provided with a longitudinal slit with parallel walls formed therein extending from side to side thereof and alined openings in the upper and lower portions of said thicker end perpendicular to said slit, the opening in the outer portion being of less diameter than the opening in the other portion which is provided with a downturned lip in front of the thinner end; and a cutting member rigidly secured in the thinner end in alinement with said openings and with its outer end normally positioned in the larger opening.

Signed by me at 4 Post Office Square, Boston, Massachusetts, this 13th day of September, 1918.

GEORGE W. PROUTY.
